UNITED STATES PATENT OFFICE.

PETER G. JOHNSON, OF RILEY CENTRE, KANSAS.

DESIGN FOR A WING CULTIVATOR-SHOVEL.

SPECIFICATION forming part of Design No. 16,889, dated September 7, 1886.

Application filed August 11, 1886. Serial No. 210,618. Term of patent 14 years.

To all whom it may concern:

Be it known that I, PETER G. JOHNSON, a citizen of the United States, residing at Riley Centre, in the county of Riley and State of 5 Kansas, have invented and produced a new and original Design for a Wing Cultivator-Shovel, of which the following is a specification, reference being had to the accompanying drawings, forming part thereof.

10 Figure 1 is a view in perspective of my newly-designed wing cultivator-shovel, and Fig. 2 a transverse section through the shank of said shovel upon the line $x-x$ in Fig. 1.

15 My design consists in a novel configuration of the wing-cutter and shank of the shovel, as hereinafter described, and shown in the accompanying drawings.

20 A is the wing-cutter, and B the body or shank of the shovel. The wing-cutter A, which is of a straight configuration, or mainly so, forms an acute angle with the shank B of the shovel, inclining upward, and is of a flat contour on its surface, which flattened contour is extended 25 to and throughout the junction b of said cutter with the body or shank B. From the junc-

tion b the shank B, which has its longitudinal edges c c parallel, or nearly so, is shaped to gradually assume a concave form on its inner surface, d, and convex form on its exterior surface, e, in transverse section, which curved 30 configurations are continued throughout the whole remaining length of the shank.

I claim—

The design for a wing cultivator-shovel herein shown and described, the same consisting 35 of a straight or approximately straight wing-cutter, A, of flat contour on its surface, and a shank, B, the two presenting an acute-angled figure with the cutter inclining upward, and the shank B being of concave form on its interior, d, and convex shape on its exterior, e, in transverse section throughout its length, but gradually assuming a flat contour corresponding with that of the wing-cutter at and throughout the junction b of said cutter with 40 45 said shank.

PETER G. JOHNSON.
